E. E. GREVE

SUCKER ROD ELEVATOR

Filed Jan. 29, 1924

INVENTOR

UNITED STATES PATENT OFFICE.

EDGAR E. GREVE, OF BELLEVUE, PENNSYLVANIA.

SUCKER-ROD ELEVATOR.

Application filed January 29, 1924. Serial No. 689,266.

This invention is for an elevator for handling the sucker rod or sections thereof in and about oil well derricks.

In wells that are being pumped, it is necessary to employ a sucker rod elevator in the derrick, by means of which the sucker rod, or sections of said rod, may be manipulated. As originally designed, such elevators did not retain the sucker rod in their grip under all circumstances, sometimes permitting the rods to drop into the hole, causing damage and expense. Attempts have been made to provide safety catches for these elevators, frequently weakening the elevator or necessitating such heavy construction as to make the elevators awkward and clumsy to handle.

The present invention has for its principal object to provide an elevator which may be made relatively light and which will effectively hold the sucker rod against accidental release.

Further objects of the invention are to provide, in a sucker rod elevator, a leading-in passage of novel design which will of itself tend to prevent accidental release of the sucker rod, and also to provide a movable locking pin so positioned with respect to the leading-in slot that any movement of the sucker rod toward released position tends to move or hold the locking pin more effectively into or in locking position.

These and other objects and advantages are obtained by the present invention, which is illustrated in the accompanying drawings, and in which:

Fig. 1 is a top view of an elevator embodying my invention;

Fig. 2 is a longitudinal vertical section in the plane of line II—II of Fig. 1; and

Fig. 3 is a top plan view of a slightly modified construction.

In the drawings, 5 designates a suitable body having transversely extending trunnions 6 thereon, over which the ends 7 of a suitable bail or other suspending means are fitted, to rotatably support body 5. At 8 are pins for retaining the bail ends 7 in place.

Formed in the body 5 is a vertical leading-in slot 9, whose outer end is located at one side of the center of the block, the slot curving sharply some distance in from its outer end, and terminating in central vertical opening 10, said slot therefor being non-radial with respect to said opening. The

central vertical opening may, if desired, have a removable liner or bushing 11 therein, as shown in Figs. 1 and 2. This bushing has a flanged upper end received in a recess in the top of body 5 to hold the bushing against downward movement, and screws 12 may be utilized to hold the bushing in place. Bushings of different sizes may, by this arrangement, be inserted when necessary.

The parts of the body at the peripheral terminal of the leading-in slot are rounded, as shown at 5', to facilitate the guiding of the elevator onto the rod.

In Figs. 1 and 2, the body 5 has a radial extension 13. A radially extending hole 14 is formed in the body 5 and in the extension, the inner end of the hole terminating short of the central hole 10. At one side of the inner end of hole 14 is a smaller offset hole 15, which is tangentially disposed with respect to opening 10, the hole opening into slot 9.

Screwed into the outer end of hole 14 in extension 13 is a threaded bushing 16 having a central recess 17 and a central hole 18. This bushing provides a bearing for a rod 19 that passes through it, the inner end of the rod having a head 20 thereon. Carried on this rod is a locking member 21 having a recess therein to receive the head 20 on rod 19, and having an offset extension 22 that projects through hole 15 into leading-in slot 9 at the curve thereof, this extension being substantially tangential to the central opening. A compression spring 23 surrounding rod 19 and confined between member 21 and bushing 16 serves to yieldably urge the locking member toward extended or locking position.

A knob 24 is secured to the outer end of rod 19, and provides manual means for retracting the locking member against the action of the spring.

So far as I am aware, it has not heretofore been proposed to utilize, in a sucker rod elevator, a curved or other non-radial leading-in slot.

In operation, the sucker rod is forced into the slot 9, until it contacts with the extended end 22 of the locking device. Upon being further pushed, the sucker rod will force the extension rearwardly until the sucker rod can pass it and move into the central hole. The end of the extension 22 is preferably slightly beveled in order to allow the sucker rod to more readily clear it. When

the sucker rod has been forced into the center of the block, spring 23 immediately snaps the locking member back into projected or extended position.

5 The shape of slot 9 as it is, is such that once the rod is in place, it would not readily slide out of the slot of its own accord, even if the locking means were not provided. However, the locking extension serves to 10 confine the rod to the inner end of the slot, and any tendency of the rod to move out of the slot tends to move or hold the locking member into or in locking position.

When it is desired to release the rod, knob 15 24 may be pulled to retract the locking means, after which the rod may be guided out of the groove.

In the construction shown in Fig. 3, the arrangement is a little more simple. In 20 this view, the body 5 and the slot 9 and associated parts are generally similar to the construction shown in Fig. 1, the removable bushing, however, not being shown. The main difference is in the locking device, however, and similar reference characters designate the parts common to both forms.

Instead of the body having a radially extending hole, as shown in Figs. 1 and 2, body 5 in Fig. 3 has a straight hole 25 therein extending from one side thereof into the slot 9, this hole being tangential with respect to central opening 10. The body 5 has an offset extension 26 thereon, through which hole 25 also passes. Slidably received in this hole is 35 a locking pin 27 having its inner end projecting into slot 9, and having its outer end terminating in a knob 28. The pin 27 is hollow to receive a compression spring 29, and has opposed longitudinal slots 30 therein, through which a transverse pin 31 extending 40 through extension 26 passes. This pin serves to confine spring 29, whereby the spring urges the locking pin forwardly into projected or locking position.

45 The operation of this construction is similar to that described in connection with Fig. 1.

1. While it is a cheaper construction, it has a slight disadvantage in that, the operator, when applying the elevator to the sucker-rod, pushes against the elevator from the side on which the knob is located. The knob forms a convenient point at which to apply pressure. Should the operator, with the construction shown in Fig. 3, push 50 against the knob, he would prevent the locking member from yielding. In the constructions shown in Figs. 1 and 2, however, the locking member, being loose on rod 19, may move inwardly while the operator pushes 55 against knob 24. The head 20, however, causes the locking member to move back when rod 19 is pulled to retract the latch.

Various other changes and modifications 60 may be made in the construction within the contemplation of my invention.

What I claim is:

1. A sucker rod elevator comprising a body having a sucker rod receiving opening therein, said body having a curved leading-in slot extending from its periphery inwardly to said opening, and a reciprocable locking member projecting into the slot. 70

2. A sucker rod elevator comprising a body having a sucker rod receiving opening therein, said body having a curved leading-in slot extending from its periphery inwardly to said opening, and a reciprocable locking member projecting into the slot and tangentially disposed with respect to the rod receiving opening. 75

80 3. A sucker rod elevator comprising a body having a sucker rod receiving opening therein and having a curved leading-in slot therein extending from the rod receiving opening to the periphery of the body, a reciprocable locking member carried by the body projecting into the slot tangentially of the rod receiving opening, and means for yieldably urging said locking member to projected position. 85

90 4. A sucker rod elevator having a vertically extending rod receiving opening, a curved leading-in slot in communication with the opening, a reciprocable locking member operable in the curved slot, means for automatically maintaining the member in locking position, and means for manually moving said member to unlocked position. 95

100 5. A sucker rod elevator comprising a body having a sucker rod receiving opening therein and having a curved leading-in slot extending from the periphery of the body into the opening, a reciprocable locking member having an extension projecting endwise into said slot with its terminal toward the open end thereof, said extension being tangentially disposed with respect to said central opening, means for yieldably urging said extension into projected position in the slot, and operating means for the lock member. 110

115 6. A sucker rod elevator comprising a body having a centrally located vertical opening therethrough and having a curved vertical slot therein extending from the opening to the periphery of the body, said body having a horizontal hole therein extending radially from the periphery at a point substantially opposite the outer terminal of the slot inward toward the central opening, said hole being terminated short of such opening, the body also having an offset hole therein leading from the slot to said horizontal hole, the offset hole being tangentially disposed with respect to said central opening, a reciprocable rod in the horizontal opening, a locking member slidably carried on the rod at the inner end of the horizontal hole, said locking member 120

having an offset extension thereon which projects through said offset hole into said slot, a spring for normally urging the locking member into projected position, and 5 means on said rod engaging said head for enabling the locking member to be drawn by such rod to retracted position.

7. A sucker rod elevator having a vertical rod receiving opening, and a vertical outwardly extending leading-in slot communicating with the vertical opening in non-radial relation thereto.

8. A sucker rod elevator having a vertical rod receiving opening, and an outwardly extending leading-in slot communicating with the vertical opening in non-radial relation thereto, and a locking member operable within the juncture of the said slot and opening.

20 9. A sucker rod elevator having a vertically extending rod receiving opening, a curved

leading-in slot in communication with the opening, a locking member operable substantially within the juncture of said slot and opening, means for automatically maintaining the member in locking position, and 25 means for manually moving said member to unlocked position.

10. A device of the character disclosed, comprising a body adapted to be applied to work and having a vertical opening within 30 which the work is received and accommodated for support of the work by the body, said body having an outwardly extending opening communicating with said first 35 named opening in obtuse angular relation thereto; in combination with latch means disposed to operate substantially at the zone of merger of said openings to retain the work within said first named opening. 40

In testimony whereof I affix my signature.
EDGAR E. GREVE.
